MOUTH GUARD

John Hinton Shackelford, Baltimore, Md.

Application June 12, 1953, Serial No. 361,152

4 Claims. (Cl. 128—136)

The present invention relates to a mouth guard and it consists in the combinations, constructions and arrangements of parts herein described and claimed.

Generally there is provided a mouth guard which is designed to protect the natural teeth during athletic contests. The device is designed to fit over the crowns of the teeth of the upper jaw and to extend upon the tissues adjacent to the teeth thereby affording increased protection. One of the principal features of the invention is the provision of novel means whereby the device avoids all pressure upon the gingival margins of the gums. The device is adapted to fit securely around the individual teeth about two-thirds of the way toward the gum line thereby gaining a part of its retention upon the teeth from its fit thereover and a part of its retention from its extension upon the soft tissues. A clearance of contact is established from approximately the last third of the length of the crown to beyond the gum margin onto the soft tissues of the mouth to thereby avoid irritation of the user's gums. The device is of sufficient thickness, graduating from three to five millimeters over the posterior teeth to from five to seven millimeters over the anterior teeth to thereby absorb shock and prevent luxation or fracture of the teeth when the jaws are brought violently together by sudden impact. A flange of the guard, approximately three millimeters in thickness, extends upwardly into the space between the upper jaw and the cheek to protect the user's teeth from forceful impacts upon and through the cheeks of the user. The device is also helpful in preventing the upper teeth from cutting the tissues of the face at the time of such impacts. The device may be made from a variety of durable elastic materials. The device is designed to eliminate the need for costly individual impressions of each player's mouth since it is constructed in accordance with scientifically derived average measurements thereby permitting commercial production and distribution to a large number of players at reasonable cost.

It is accordingly an object of the invention to provide a device of the character set forth having novel means for protecting the gingival margins of the gums of the user.

Another object of the invention is to provide a device of the character set forth which is simple in construction, inexpensive to manufacture and yet effective and efficient in use.

A further object of the invention is to provide, in a device of the character set forth, novel means for protecting the tissues adjacent the teeth of a user.

Another object of the invention is the provision, in a device of the character set forth, of novel means for retaining the same upon the user's teeth.

A still further object of the invention is the provision of a device of the character set forth which lends itself to manufacture in standardized sizes.

Other and further objects of the invention will become apparent from a reading of the following specification taken in conjunction with the drawing, in which:

Figure 1 is a side elevational view, partly broken away, of an embodiment of the invention shown in operative position upon the teeth of an upper jaw,

- 5 Figure 2 is a front elevational view thereof,
Figure 3 is a bottom plan view thereof,
Figure 4 is a top plan view of the device illustrated in Figures 1 to 3, inclusive,
Figure 5 is a sectional view taken substantially along line 5—5 of Figure 4, and
10 Figure 6 is a greatly enlarged sectional view taken substantially along line 6—6 of Figure 1.

Referring more particularly to the drawing, there is shown therein, in Figure 6, a molar tooth generally designated at 10 and consisting of pulp tissues 11, dentin 12 and enamel 13. The tooth 10 is provided with the usual roots 14 embedded in the alveola bone 15 of the jaw and which roots 14 are provided with the periodontal membranes 16. At 17 is shown the customary mucous membrane of the mouth and at 18 the gingival margin of the gum. The dotted line 19 represents the greatest width of the exposed portion of the tooth 10 and will hereinafter be referred to as the "height of contour" of the tooth 10, it being understood that all of the molar teeth encompassed by the device of the present invention are likewise provided with a "height of contour" and that, in any particular jaw structure, such "height of contour" lines are in substantial horizontal alignment.

The device comprising the present invention is generally designated at 20 and is formed of a single piece 30 of plastic material having a desired degree of flexibility and consists of a base portion 21 whose outer or lower surface 22 is slightly convex as clearly shown in Figure 6 but which lies generally in the same horizontal plane. The upper face 23 of the base 21 is irregularly shaped 35 to substantially comply with and complement the contours of the lower faces of the teeth 10 of the upper jaw of the user.

The device further comprises an integrally formed upwardly extending inner wall 24 adapted to encompass 40 the inner sides of the teeth 10 and bear against the marginal portions of the mucous membrane of the roof of the user's mouth. There is also provided an integrally formed upwardly extending wall 25 which is adapted to encompass the outer faces of the teeth 10 and the adjacent portions of the mucous membrane of the mouth and lie between such membrane and the cheeks of the user.

Both of the walls 24 and 25 taper slightly toward their 50 upper edges to relatively narrow rounded upper edges 26. Each of the inner faces of the walls 25 and 24 is provided with a concave portion 27 adjacent the base 21 which concave portions are adapted to closely encompass the enameled portion of the teeth 10 to points upwardly beyond the "height of contour" 19 of the teeth 10 and each of the inner faces of the walls 24 and 25 is provided with an upper concave portion 28 providing in each case an opening 29 between the inner face of the respective wall and the gingival margins 18 of the gum. These spaces 29 of course extend in a general horizontal 60 direction throughout the entire wall structures.

In operation, it will be apparent that the mouth guard 20 may be quickly and easily positioned upon the teeth of the upper jaw of the user as shown, for example, in Figure 1 of the drawing. This is accomplished by placing the device immediately beneath the teeth and then pressing the device upwardly during which operation it will be seen that the walls 24 and 25 will first be forced apart as they approach the "height of contour" lines of the teeth 10 after which the walls 24 and 25 will return 70 inwardly toward each other through the natural elasticity of the material from which the device is made. Since now the concave portions 27 embrace each tooth

10 beyond the "lines of contour" 19 it will be readily apparent that the guard 20 will be securely mounted upon the teeth against accidental displacement therefrom. It will also be seen that the space 29 will fully protect the sensitive gingival margins 18 of the gums since such spaces 29 prevent all contact between such margins 18 and the body of the guard 20. When the device is so mounted in the user's mouth, it will further be held in position by contact with the teeth, indicated at 30, of the lower jaw but it will be readily apparent that the device will at all times remain upon the teeth of the upper jaw so that there will be no interference with the breathing of the user. The upper edges 26 of the outer wall 24 are provided with indentations 31 to accommodate the contour of the adjacent portions of the user's 15 mouth.

While but one form of the invention has been shown and described herein, it will be readily apparent to those skilled in the art that many minor modifications may be made without departing from the spirit of the invention or the scope of the appended claims.

What is claimed is:

1. A device of the character described comprising a substantially horizontal base, an upwardly extending outer wall, and an upwardly extending rear wall, said walls 25 being formed integrally with said base and adapted to encompass with said base the teeth and gums of the upper jaw, said device being formed of a yieldable material, said walls each being provided in its inner face with a generally horizontally extending groove, and said 30

grooves adapted to encompass in spaced relation the gingival margins of said gums.

2. A device of the character described comprising a substantially horizontal base, an upwardly extending outer wall, and an upwardly extending rear wall, said walls being formed integrally with said base and adapted to encompass with said base the teeth and gums of the upper jaw, said device being formed of a yieldable material, said walls each being provided in its inner face with a generally horizontally extending groove adjacent said base, said grooves being of arcuate shape in vertical cross sectional area and each being adapted to encompass the outer portions of said teeth to points beyond their greatest width.

3. A device as defined in claim 1 wherein said walls are each provided in its inner face with a generally horizontally extending groove adjacent said base, said grooves being of arcuate shape in vertical cross sectional area and each being adapted to encompass the outer portions of said teeth to points beyond their greatest width.

4. A device in accordance with claim 3 wherein said base is provided with an irregularly shaped upper face adapted to complement the outer faces of teeth placed thereagainst.
